TWO-PART AXIAL SPACER FOR
TRANSFORMER WINDINGS

Oliver M. Olivier, McKees Rocks, Pa., assignor to
Allis-Chalmers Manufacturing Company, Milwaukee, Wis., a corporation of Delaware

Application May 16, 1949, Serial No. 93,468

4 Claims. (Cl. 175—362)

1

This invention relates in general to stationary induction apparatus and particularly to spacers for positioning the coils of the windings of transformers and other induction apparatus.

In the prior art, coaxial windings of induction apparatus have been spaced from one another and from insulation barriers by the use of narrow pressboard strips or sticks. In this manner uniform annular spaces are formed between stacks of windings and between windings and barriers, and the stacks of windings are held in position. However, these spacer strips or sticks are difficult to insert after the windings are assembled, and the spacers may be inserted improperly. They may become displaced or may shift from proper position, and as a result, the coils of the windings may become displaced.

In transformers or reactors where one of the windings comprises a stack of disk type coils, it is difficult to insert spacer strips or sticks between the stack of coils and the barrier which is next to the stack of coils. Entry of the sticks is obstructed by the edges of individual disk coils in the stack which edges protrude slightly and irregularly into the space between the coils and the barriers. When assembling these windings, layers of disk coils are superposed with radial spacers between the layers to provide space so that insulating fluid can circulate between layers. Each of the coils has an edge on the inner periphery of the stack and another on the outer periphery, and it is not feasible to perfectly align these edges when one coil is placed over another with radial spacers therebetween. As a result neither the inner nor the outer peripheral surfaces of the windings are perfectly smooth.

Means have been suggested to guide the entry of the spacer sticks which are inserted between the stack of winding and the barriers. However, the prior art does not suggest how to provide proper and easy entry of the spacer sticks. The difficulties resulting because of edges of coils or of radial spacers protruding unevenly from the stack has not been avoided in the prior art. The protruding portions of radial spacers may become torn and displaced; the insulation on the disk coils may become torn, and the spacer sticks may be damaged.

It is very important that twisting or shifting movement of the stack of disk coils with respect to the other windings or insulating barriers in electric induction apparatus be completely avoided. Movement may result while the apparatus is in transit or under conditions of energization and use when there are high stresses on the windings.

2

Therefore it is necessary to firmly hold the stack of coils in position and also important that the stack be perfectly aligned with respect to the insulation barrier and other windings. Any misalignment or displacement of the coils with respect to the insulation barriers or other parts of the structure of the apparatus will result in unnecessary stresses in the apparatus when it is energized and used.

10 To assure the proper alignment of the coils of the stack and also to avoid the possibility of twisting or shifting of the coils in transit or when excited for use, the vertical spacing sticks between a stack of coils and a barrier should be slightly greater in thickness than the width of the annular cylindrical space between the stack of coils and the barrier. The oversized spacing stick can be inserted in the space between the coils and barrier, because of the resilience of the coils. The coils are thereby snugly positioned. However, since the cylindrical space between the coils and barrier is not wider than the spacer strip to be inserted therebetween, it is necessary to have means by which the strip can be inserted 20 without being obstructed by the uneven or protruding edges of coils or radial spacers between layers of coils. The possibility of not inserting the stick properly and vertically must be avoided.

The disadvantages of the prior art have been avoided by the present invention. One of the 30 objects of the invention is to provide an improved means for spacing a stack of disk coils from other windings or from an insulation barrier in an electric induction apparatus.

Another object of the invention is to provide 35 improved means by which vertical spacers may be inserted between a stack of coils and an insulation barrier in electric induction apparatus.

Still another object of the applicant's invention is to provide improved means for firmly and securely fixing windings in electrical induction apparatus.

These and other objects of the invention which will hereinafter become apparent are accomplished by means of a spacer for use in electric induction apparatus such as above referred to, wherein an element of the spacer can be anchored in position with respect to the windings and the barriers and another element of the spacer can be inserted with one side bearing on the surface of the barrier and the opposite side bearing on a surface of the anchored element thereby causing forces to be exerted on the stack of coils to firmly, snugly and properly position the stack of 50 coils.

In the drawing:

Fig. 1 is a view in longitudinal cross section of part of a core type transformer provided with spacers built in accordance with the present invention;

Fig. 2 is a partial cross sectional view of the transformer shown in Fig. 1 taken along line II-II of Fig. 1;

Fig. 3 is an enlarged view in elevation of the spacer shown in Fig. 1 and of a portion of the adjacent barrier;

Fig. 4 is a plan view of the spacer and barrier portion shown in Fig. 3;

Fig. 5 is a view in elevation of the grooved strip element of the spacer shown in Fig. 3;

Fig. 6 is a side view of the grooved strip shown in Fig. 5; and

Fig. 7 is a plan view of the grooved strip shown in Fig. 5.

The transformer, of which only a portion is shown in Figs. 1 and 2, includes a magnetic steel core with high and low voltage windings surrounding a leg of the core.

The low voltage winding 12, 13 is cylindrical in form. The two sections 12, 13 of low voltage winding are separated from each other by spacers 14 and are insulated from the laminated iron leg member 15 of the core by the wound insulation or foundation member 16. In the structure shown, wooden members 17 are used to space section 12 of the low voltage winding from the core steel.

A stack of high voltage windings 20 of the disk type are shown. Radial spacers 21 are inserted between the layers of the disk coils separating the coils from each other thereby insuring the circulation of air or oil to the individual coils in the winding stack.

Cylindrical insulation barriers 24, 25, 26 are positioned between low voltage winding 12, 13 and the stack of high voltage coils 20 for insulating purposes. The insulation barriers are spaced from each other and from the low voltage windings by spacers 27 which are circumferentially spaced from each other and are radially aligned with spacers 21.

In building transformers such as the one represented in Figs. 1 and 2 the sections of low voltage winding and the insulation barriers are not too difficult to place in position as both the low voltage windings and the barriers all are of cylindrical form. However, the high voltage winding, which is a stack of disk coils 20, is not so easy to position with respect to the insulation barriers and the other elements of the transformer. The high voltage stack must be firmly and snugly held and properly positioned with respect to the other elements of the transformer. And since the high voltage stack is assembled by superposing one disk coil 20 over another with radial spacers 21 therebetween, the surface 31 defined by the inner edges of these individual disk coils, which surface will be referred to as the inner peripheral surface of the high voltage stack, is irregular compared with the smooth surfaces of the barriers and of the low voltage winding.

Also, the stack of disk coils is usually assembled after the other parts of the structure are assembled, and it is desirable to space the stack from the nearest barrier after the complete high voltage stack is assembled. The present invention provides a novel and efficient means for spacing the entire stack of high voltage coils from the nearest barrier after assembly. This will be

hereinafter described in full. This spacing means is referred to by the reference numeral 33.

In the transformer shown the high voltage stack and the low voltage windings are supported 5 and insulated from the yoke members 34, 35 of the core and from the heavy reinforcing channel members 36, 37 which are over the yoke members, by built-up insulation 38, 39 at each end of the winding assembly. In addition, insulation washers 40, 41 and spacers 42, 43 increase the spacing 10 between the high voltage stack and the yokes and channel members. Standard insulation is intended to be represented by numerals 38 to 43. This includes yoke pads, washers, washer fillers, 15 spacers and built-up blocks.

An electrostatic plate 44 may be placed next to the line end of the stack of coils in order to provide distribution of impulse voltages across the first coil.

The complete winding assembly, including the high voltage and low voltage windings with the insulation and padding, is clamped between the channel members 36, 37 by strong tie rods (not shown). Also, bolts (not shown) through the 20 channel members are used to clamp the core and the mechanical parts. Clamping tie rods and bolts are employed in conventional manner for this type transformer.

The spacing means represented by numeral 33 30 is used for snugly fixing the stack of high voltage disk coils 20 in place and uniformly spacing the stack from the insulation barrier.

The spacer means consists of a plurality of 35 spacer assemblies circumferentially spaced about barrier 26. Each assembly is made of two parts. One part 45 is a grooved spacer element of press-board or similar laminated cellulosic insulating material. The other part 46 of the spacer means is a drive stick made of laminated synthetic resin or other insulating material. The drive stick 46 is driven between the grooved strip and the barrier, and thus tightens and positions the stack.

In Figs. 3 to 7 one of the spacers of means 33 is shown. Pressboard or other similar insulating material is cut to the rectangular shape of the strip outlined in Fig. 5. Then the central portion 47 of the strip is scored lengthwise thereof along lines 48 and 49 by a saw or knife cut. The press-board is scored only through part of the thickness of the strip and then the material between lines 48 and 49 is removed from the strip. Numeral 60 represents the depth of the saw cut which will usually extend to a slightly greater depth than the thickness of the layers of laminations which are removed. Thus one side of the strip member 45 has a rectangular recess 51 formed therein having sides along lines 48 and 49 and a base therebetween along line 52. The opposite side 53 of the strip 45 has a flat surface. The grooved spacer strip with only the longitudinally extending portion removed may be satisfactory for use in many transformers. However, at times it may be desirable and important that the end portions 55, 56 of the grooved strips be flat. In such instances, the strip member 45 is scored along lines 58, 59 crosswise of the direction of the lengthwise groove. The pressboard material between the scored line 58 and the end 62 and between line 59 and the end 61 is removed to a depth not greater than the depth of scored lines 58, 59 so that the end portions 55, 56 are flat. Thus the ends of these strips which are bent along lines 64, 65 and extend radially below and above the stack of disk coils have a substantially

flat surface, and the strip is firmly and tightly held in position by the stack.

A similar spacer strip can be made by other methods, such as by building up the laminations to the final form indicated in Figs. 5, 6 and 7.

In the assembly of a transformer such as the one shown, when the low voltage winding 12, 13 and the insulation barriers 24, 25, 26 are in place surrounding the core member 15, several of the grooved strip elements 45 are circumferentially spaced from one another around the insulation barrier 26, with the portion intermediate the end portions 55, 56 extending in a lengthwise direction parallel to the axis of the barrier 26. The end portion 55 is bent at an angle 90° to the intermediate portion along line 55 and the end portion 55 extends over the yoke padding 39. The insulation washers 41 and spacers 43 are placed over the end portions 55 of the several grooved strip elements. Radial spacers 21 are circumferentially spaced from each other on top of the spacer 43. Then the disk coils 20 are placed about the core member 15, the low voltage winding 12, 13 and barriers 24, 25, 26. The first disk coil 20 rests upon the radial spacers 21, and the grooved strip elements are thereby anchored in position. The entire stack of disk coils is assembled. Spacers 42 and washers 40 are placed over the stack, and then end portions 56 of the strips are bent along line 64 at an angle of 90° to the intermediate portion of the strip so that the end portions 56 extend over the disk coils and the insulation washers and spacers.

After the high voltage stack is assembled a driving stick preferably with at least one end 67 tapered is driven between the barrier 26 and each grooved spacer element 45. The stick 46 is approximately as wide as the width of the groove. The thickness of the stick is greater than the depth of the groove. Therefore, when the stick is driven between the barrier and the strip, the stick forces the strip away from the barrier, thereby spacing the stack of disk coils from the barrier. Entry of the stick after assembly of the stack of coils without damage to the stick or coil insulation is assured by the use of the grooved strip. The driving stick is retained in the groove of the strip while one side 69 of the driving stick bears against the comparatively smooth surface of the strip and the other side 68 of the driving stick bears against the smooth outer surface of the barrier.

The spacer means including the driving stick and the grooved strip can be slightly greater in thickness than the width of the space between the barrier and stack before the stick is inserted therebetween. Thus, when the stick is inserted, the width of the space is slightly increased because of the resilience of the disk type coils of the high voltage winding. In this manner the stack of disk coils is firmly and snugly positioned. After the spacer is properly positioned, the padding 38 is placed in position over the winding assembly.

The yoke member 34 and channel member 36 are then put in position. Rods and bolts are added to the structure between channel members clamping the entire unit in the usual manner to give strong mechanical support to the windings and coils.

Although but one embodiment of the present invention has been illustrated and described, it will be understood by those skilled in the art that various changes and modifications may be made therein without departing from the spirit

of the invention or from the scope of the appended claims.

It is claimed and desired to secure by Letters Patent:

1. An electric induction apparatus including a cylindrical insulation barrier, a stack of disk coils surrounding said barrier and radially spaced from said barrier to form an annular cylindrical passageway between said barrier and said stack of coils, means for spacing said coils from said barrier, said means including spacers extending in a direction parallel to the longitudinal axis of said barrier, said spacers being circumferentially spaced from each other in said passageway, each of said spacers comprising a strip of insulating material having a flat side bearing against the edges of said disk coils and extending from one end of said stack to the other end of said stack, the opposite side of said strip having a recess extending lengthwise parallel to the axis of said stack, the end portions of said strip being bent and extended over the ends of said stack so that said strip is firmly held in position relative to said stack, and a stick of insulating material having a thickness greater than the depth of said recess inserted in said recess and extending at least from one end of said stack to the other end thereof with opposite sides of said stick bearing against the surface of said barrier and against the base of said recess.

2. An electric induction apparatus including a cylindrical insulating barrier, a plurality of disk coils constituting a winding surrounding said barrier, said winding having resilience to forces acting radially on the edges of said coils, said winding being radially spaced from said barrier to define an annular cylindrical passageway between said barrier and said winding, and means for snugly holding said winding with respect to said barrier comprising a plurality of spacers circumferentially spaced in said passageway, one of said spacers comprising a strip of insulating material extending lengthwise at least from one end of said winding to the other end thereof, the end portions of said strip being bent and extending over the ends of said stack so that said strip is firmly held in position relative to said stack, a first side of said strip facing said barrier and having a groove therein extending lengthwise of said strip, the opposite side of said strip bearing against said winding, and a stick of insulating material inserted between and abutting against said barrier and said strip with said stick partly retained in said groove, said one of said spacers having a radial thickness slightly greater than the radial distance between said winding and said barrier, whereby insertion of said stick into said groove causes local radial deformation of said winding to maintain said one of said spacers in place by the resilience of said winding.

3. An electric induction apparatus including a winding having resilience to forces acting radially from the axis thereof, an insulating barrier coaxially disposed with respect to said winding, and means firmly positioning said winding in radial spaced relation with respect to said barrier by slightly increasing the distance between local areas of the adjacent peripheral surfaces of said winding and of said barrier, said means including a spacer comprising a strip of insulating material inserted between said barrier and said winding and extending in a direction parallel to the longitudinal axis of said winding from at least one end 70 of said winding to the other end thereof, said

strip having a longitudinally extending groove in a side thereof facing said barrier, and an insulating stick retained in said groove and bearing on said strip and said barrier, said spacer having a radial thickness slightly greater than the radial distance between said winding and said barrier, whereby insertion of said stick into said groove causes local radial deformation of said winding to maintain said spacer in place by the resilience of said winding.

4. An electric induction apparatus including a cylindrical insulating barrier, a plurality of superposed disk coils surrounding said barrier, said coils being formed of conductive material spirally wound layer over layer and having resilience to forces acting radially on the edges of said coils, and spacing means for snugly holding said disk coils with respect to said barrier, said means including a strip of insulating material having one side bearing against the edges of said coils and having a recess in the opposite side of said strip extending parallel to the longitudinal axis of said barrier, and an insulating stick inserted in said

10

15

recess with opposite sides bearing against said barrier and against the base of said recess, the assembly comprising said stick and said strip having a radial thickness slightly greater than the radial distance between said coils and said barrier, whereby insertion of said stick into said recess causes local deformation of said coils to maintain said assembly in place by the resilience of said coils.
